UNITED STATES PATENT OFFICE

ALBERT W. LINDQUIST, OF PROVIDENCE, RHODE ISLAND, ASSIGNOR TO FREEMAN-DAUGHADAY COMPANY, A CORPORATION OF MASSACHUSETTS

DESIGN FOR A CLIP FOR NECKTIES OR THE LIKE

Application filed November 19, 1930. Serial No. 37,705. Term of patent 7 years.

To all whom it may concern:

Be it known that I, ALBERT W. LINDQUIST, a citizen of the United States of America, residing in Providence, county of Providence, State of Rhode Island, have invented a new, original, and ornamental Design for a Clip for Neckties or the like, of which the following is a specification, reference being had to the accompanying drawing, forming a part thereof.

Fig. 1 is a top plan view of a clip for neckties or the like, showing my new design; and Fig. 2 is a side elevation of the same.

I claim:

The ornamental design for a clip for neckties or the like, substantially as shown.

ALBERT W. LINDQUIST.
